UNITED STATES PATENT OFFICE.

CHARLES H. NICKERSON, OF DERRY, NEW HAMPSHIRE.

LASTING-SHELL AND UPPER-PROTECTOR.

1,134,284.

Specification of Letters Patent.

Patented Apr. 6, 1915.

Application filed May 11, 1914. Serial No. 837,644.

To all whom it may concern:

Be it known that I, CHARLES H. NICKERSON, a citizen of the United States, and a resident of Derry, in the county of Rockingham and State of New Hampshire, have invented certain new and useful Improvements in Lasting-Shells and Upper-Protectors, of which the following is a full, clear, and exact description.

10 The purpose of this invention is the construction of a shell which can be applied upon a shoe-upper after the latter has received the last, in order both to protect such uppers against being soiled or otherwise marred, and to secure the uppers in place on the lasts.

Referring to the drawings forming part of this specification, Figure 1 is a perspective view of a shell embodying my invention. Fig. 2 is a plan view of an upper secured in place upon a last by the shell. Fig. 3 is a cross section of a last, upper and shell. Fig. 4 is a side elevation of a shell, an upper and a cloth protector, the latter being in section. Fig. 5 is a perspective view of the fastening device used in connection with the shell. Fig. 6 is a plan view of another form of the shell.

The shell 1 which constitutes the main portion of my invention, may, when designed to be used for protecting white or tan uppers, be formed from press board and the like; but in case it is to be employed for fastening purposes, or both fastening and protection, I prefer to have it made from metal, as sheet steel. The preferred form of the shell, which is shown in Fig. 1, conforms in shape to the lower portion of a shoe, but cut apart in a vertical line at the heel and united at the toe. The entire lower edge of the shell is curved slightly inward, as shown in Fig. 3, so that when the same is clamped about a last 2, the latter is firmly held. The reference numeral 3 designates said incurved edges.

An upper 4 having been applied to a last 2 in the usual manner, the shell 1 is spread enough to have its incurved edges 3 pass the wider portions of the last and to present said edges flush with the bottom of the last. The vertical edges of the split heel, 5 and 6, are then forcibly drawn toward each other until the shell is firmly clamping the upper between itself and the last. The means illustrated for thus drawing the edges 5, 6 toward each other, and shown in Figs. 1, 2

and 5, consists of a section of strong spring wire having its intermediate section formed into a helix 7, one terminal section 8 formed with an eye 9 and the other terminal section 10 formed with a hook 11. Said eye is attached to the wing 12 of said shell in any suitable way, as by a rivet 13, while the hooked terminal can be engaged with any one of the plurality of rivets 14 projecting from the wing 15.

After the upper has been firmly clamped upon the last by means of the shell 1, the sole can be attached to the upper in any of the well known ways, but without tacking the edges of the upper to the last. For instance, this permits of a stitch-down shoe being made; a flexible shoe without insole; a welt shoe; a turn shoe, and a Goodyear welt shoe. It also permits a fair-stitch to be made.

Equally as valuable is the function of protection performed by means of this lasting shell, for which purpose the shell may be composed of some cheaper material, as the press board already referred to. For protecting low shoes, the shell alone is sufficient, but for high lace or button shoes, such as shown in Fig. 4, a cloth 16 is first placed over the upper, with its edges reaching well down over the sides of the foot, after which the shell 1 is applied, and by its grip upon the edges of said cloth, fastens the latter in place as well as the upper itself. After stitching the sole and upper together, and finishing up the same, the shell and cloth are removed and used over again any number of times.

In the ordinary manner of shielding white and tan shoes, wherein the cloth is stitched to the upper, and cut away after the shoe is finished, such cloth has to be thrown away, and in addition considerable work requires to be expended in picking out the threads. My shell, hence, permits the shoe to be thoroughly protected at comparatively no expense.

Although I prefer to have the shell 1 separable at the heel as above described, the heel section 20 and the toe section 21 may be slidably united, as shown in Fig. 6, and said parts drawn together by tension springs 22.

The main value of my invention when used for the lasting of a shoe, is that the upper is drawn down to the last and held securely, ready to make a stitch down, turn

or welt shoe without the use of an inner sole or the use of any tacks.

What I claim as my invention is:

1. The combination with a shoe last, of a shell snugly fitting the lateral surface thereof but leaving the under surface exposed, said shell being cut apart on a vertical line, and means for forcibly drawing toward each other the edges of said cut shell.
- 10 2. The combination with a last, of a shell inclosing the sides thereof but leaving the under surface of the last exposed, the heel

of said shell being cut apart on a vertical line, said shell having means for forcibly drawing toward each other the edges of 15 the cut shell.

In testimony that I claim the foregoing invention, I have hereunto set my hand this 5th day of May, 1914.

CHARLES H. NICKERSON.
